UNITED STATES PATENT OFFICE

OSCAR H. JOHNSON, OF PETALUMA, CALIFORNIA

COVER FOR EGG CASES

Application filed March 8, 1930. Serial No. 434,262.

The present invention relates to improvements in covers for egg cases and the like, and its principal object is to provide a cover that may be quickly fastened to the case and quickly removed from the case, and that is made interchangeable for cases of the same character.

A further object of the invention is to provide a cover of the character described that 10 permanently carries the means for fastening the same to a case and that utilizes for this purpose cleats ordinarily provided in the proper place on standard egg cases.

A further object of the invention is to provide fastening means for a case cover of the character described that will take up very little space when not in use and will allow a plurality of covers to be stacked for shipping purposes without interference by the 20 fastening means.

A further object of the invention is to provide a fastening means of the character described that is simple and at the same time substantial and that firmly holds the cover 25 to the case without any possibility of accidental removal, while at the same time the fastening means yield very readily to proper manipulation for removing the cover from the case.

Further objects and advantages of my invention will appear as the specification proceeds.

The preferred form of my invention is illustrated in the accompanying drawings, 30 in which

Figure 1 shows a perspective view of an egg case having my cover fastened thereto;

Figure 2 a top plan view of the same;

Figure 3 a side elevation of the same;

Figure 4 an end elevation thereof;

Figure 5 a perspective detail view of the fastening means;

Figure 6 a vertical section taken along line 6—6 of Figure 2; and

Figure 7 a detail view of a plurality of covers in stacked relation.

While I have shown only the preferred form of the invention I wish to have it understood that various changes or modifications 50 may be made within the scope of the claims

hereto attached without departing from the spirit of the invention.

In its preferred form my invention comprises a case or box 1, a cover 2, and means for fastening the ends of the cover to the case 55 indicated at 3.

The case itself may be of any suitable kind and preferably comprises a rectangular box of standard size and proportions, such as are now commonly used for the storing and shipping of eggs. It is evident, of course, that my invention is not confined to egg cases but may be used in connection with other boxes or cases serving similar purposes.

The case as presented is provided with 60 cleats 4 and 5 along the top and bottom edges of the end pieces. These cleats are part of the standard boxes, and in my invention I use the top cleats to co-act with my fastening means in holding the cover to the case. The cover 2 is preferably made in the customary manner so as to substantially correspond to the bottom of the case, and to entirely cover the contents of the case, the edges of the cover resting on the top edges of the case.

The cover also has cleats 6 fastened to the ends thereof, by any suitable means and these cleats, which extend completely across the face of the cover, are formed with grooves 7 in the bottom adapted to receive the upper section 8 of a loop 9 shown in detail in Figure 5 so that the loop is hinged between the cleat 6 and the cover, and is adapted for encircling engagement with the cleat 5 secured to the case.

The upper section 8 of the loop is split at the center and the two ends 10 are turned over at right angles to the plane of the loop whereby endwise motion of the two parts of the upper section, and withdrawal of the same, is prevented. The cover 2 is slotted in the ends as shown at 11 so as to allow the two ends 10 to move in the slot while the loop is moved between the active position shown in Figure 1 and the inactive position, adjacent the bottom of the cover, shown in Figure 7. When the loop is in active position the two bent ends 10 bear against the bottom face of the cleat 6 and the latter is preferably reinforced by means of a small 100

plate 12 or any other suitable reinforcing means such as a simple staple or the like.

As was stated before, the cleats 5 are a part of the standard box but there is a slight variation in the width of the cleat 5, some boxes having cleats one and one-half inches wide, and others slightly less or more. In order to make any cover adaptable to these variations, I provide curvatures in the loops, 5 a curvature 13 in the bottom being particularly adapted for adjusting the loop to different sizes of cleats, while curvatures 14 in the sides of the cleat aid in adjusting the size of the loop while at the same time they 10 serve the purpose of facilitating manipulation of the loop for opening the case.

The advantages of my invention will be readily understood from the foregoing description. When the cover is not in use the 20 two loops may be swung upward against the bottom face as shown in Figure 7, and any number of covers may be piled into a stack for shipping or storing purposes. To apply the cover to the box, a person causes the two 25 loops to assume a downward position, and then placing the cover over the box, causes one of the loops to engage with one of the cleats 5, whereupon the cover is dropped upon the case, which will cause the second loop to 30 automatically engage with the second cleat 5. It should be understood that the angularity of the two ends 10 of the loop is such that when the loop is brought into vertical position there will be a certain spring tension 35 tending to urge the loop inward so that when the cover is in place the loops bear against the outer face of the box or case, and are firmly held by spring tension against accidental removal. Different widths of cleats 40 are taken care of by the different curvatures in the loops which allow of slight expansion of the latter. To remove the cover a person places his thumbs on one of the cleats 5, takes hold of the sides of the loop by means of his 45 fingers, and by a slight pressure causes the loop to clear the cleat, whereupon the end of the cover held by the operator may be raised and the opposite end may be freed by a slight forward movement.

50 I claim:

1. In combination with a case having a cleat extending across an upper edge thereof, a cover having a loop pivoted thereto adapted for encircling engagement with the cleat, and 55 means for urging the loop into contact with the cleat carrying face of the case, the loop being fashioned with offset portions along the sides and the section connecting the sides to facilitate manipulation thereof, and yielding so as to accommodate cleats of various widths.

60 2. A case cover of the character described, comprising a base, cleats fastened thereto at the ends of the base and loops hinged between 65 the cleats and the base and suspended from

the latter, the base being slotted at its ends and the loops being formed with turned over members adapted to be operated in the slots and to bear against the cleats for limiting movement of the loops.

70 3. A case cover of the character described comprising a base, cleats fastened thereto at the ends of the base, loops hinged between the cleats and the base and suspended from the latter, the base being slotted at its ends and the loops being formed with turned out 75 members adapted to be operated in the slots, and reinforcing members positioned between the base and the cleats and arranged over the slots and adapted to have the turned out members bear thereagainst for limiting the movement of the stops.
